UNITED STATES PATENT OFFICE.

CARL G. OLSON, OF CHICAGO, ILLINOIS, ASSIGNOR TO ILLINOIS TOOL WORKS, OF CHICAGO, ILLINOIS, A CORPORATION OF ILLINOIS.

GRINDER-SPINDLE.

1,393,817.

Specification of Letters Patent.

Patented Oct. 18, 1921.

Application filed May 8, 1920. Serial No. 379,737.

To all whom it may concern:

Be it known that I, CARL G. OLSON, a citizen of the United States, residing at Chicago, in the county of Cook and State 5 of Illinois, have invented a certain new and useful Improvement in Grinder-Spindles, of which the following is a specification.

My invention relates to grinder spindles and similar devices, examples of which may 10 be found in my issued Patent No. 1,232,714 granted to me July 10th, 1917, and my co-pending application, Serial No. 373,150 filed April 12th, 1920.

While grinding is not the only purpose 15 to which a device of this character may be put, I shall nevertheless describe the device primarily as a grinder, for the reason that, owing to the high speed at which grinders are rotated, my invention is particularly applicable to them.

One of the objects of the invention is to provide a device which may be operated at high speed without causing any transverse vibration or "shaking." Another object is 25 to provide a take up mechanism which will automatically compensate for wear and for lengthening and shortening of the spindle due to heating and cooling consequent upon high speed and rest, and prevent both side 30 play and end play of the spindle. Still another object is to provide means whereby the grinding wheel will yield outward (shift axially away from the housing) in case it is pressed too hard against the work. In 35 my copending application the spring disks which enable the spindle to yield axially are rotatable in unison with the spindle. One of the objects of my present invention is to obtain an analogous effect by means 40 of spring disks which, though they may creep angularly, are virtually non-rotary. It is also my purpose to accomplish these desirabilities in a simple, economical and durable manner.

45 I accomplish my objects by the mechanism illustrated in the accompanying drawings in which—

Figure 1 is an assembly view of the complete device in the form of a grinder-spindle, the housing and some of the other parts being shown in axial section.

50 Fig. 2 is a sectional view on the line 2—2, Fig. 1.

Fig. 3 is a face view of one of the dished,

annular springs which form part of the 55 take-up mechanism.

Like numerals denote like parts throughout the several views.

In the form illustrated, the housing 1 has annular end caps 2, 3 closing its opposite 60 ends. Within the housing near the forward end is a bushing 5 which is conically tapered at one end in such manner as to flare outward and form a seat for the conically tapered portion 6 of the spindle 8. 65 This sleeve or bushing may be secured in various ways, for example, it may make a press fit with the housing and thus be held frictionally as in the illustrated form. While not essential, a felt washer 9 may appropriately be interposed between the end cap 2 and the end of the housing, one of its functions being to encircle the spindle and prevent dust from entering. In addition to the conically tapered portion the bushing 75 has a cylindrical portion 10 which forms a bearing for the adjacent cylindrical portion of the spindle.

Abutting the rear end of the bushing is a set of non-rotary, resilient, dished annular disks 12 which are arranged in pairs, concavity to concavity. These disks encircle the spindle, their inner diameter preferably being such as to permit them to slide freely along the spindle. The outer diameter of 80 the disks may be varied. In the present case they are shown to be substantially equal to the inner diameter of the housing, but freely movable in it.

Abutting the innermost disk is a sleeve 90 14 which fits slidably within the housing and at the rear end abuts a ring 15 which is also slidable in the housing and forms the outer member of a ball bearing; that is, it forms the outer ball race for anti-friction 95 balls 16. The inner ball race is formed by an inner ring 18 which is annularly grooved for accommodating the balls and enabling them to exert endwise thrust upon the spindle. Ring 15 is concave on the inside when 100 viewed in axial section, with the result that it is able to exert endwise thrust upon one or the other of the two sets of balls. The inner ring 18 is held rigid on the spindle so as to move endwise in unison with it. 105 This holding may be variously accomplished, but according to the present design a shoulder 20 is formed upon the spindle to abut

one end of the ring, and the other end of the ring abuts a sleeve 21 which encircles the spindle and is held in contact with the ring by a pulley 22 which in turn is held 5 by a nut 24 screwing onto the outer threaded end of the spindle. In practice the parts 18, 21, 22 are clamped so tightly together that the pulley will drive the spindle. This construction also has the advantage of holding 10 the parts firmly together in a very simple manner.

The forward end of the spindle is provided with a chuck or appropriate equivalent thereof for holding the acting tool 15 which in the present case is shown in the form of a grinding wheel 26. The design of chuck here illustrated is the same as the one shown in my said copending application and therefore need not be described in detail. The end of the spindle is counter bored 20 to slidingly receive a holding sleeve 28 having an annular flange 29 at the outer end for retaining the grinding wheel between it and the outer end of the spindle. The inner end 25 of the sleeve has a longitudinal slot 30 adapted to receive the inner end of a pin 32 fastened to the spindle. This permits the sleeve to move lengthwise but prevents it from rotating. The sleeve is held in place 30 by a screw 34 which screws into an internally threaded counterbore 35 in the spindle. This construction prevents the negative torque of the grinding wheel when in action, creating a tendency to unscrew the parts.

35 By preference the chuck spindle has a pair of "flats" 36 on the side to enable it to be engaged by a wrench when the nut 24 is being applied or removed.

Operation: When the parts are assembled 40 there is a slight space between the outer (left) end of the conical portion 6 of the spindle and the adjacent washer 9 or end cap 2. There is also a space between the ball races 15, 18 and the end cap 3. This 45 admits of endwise movement of the spindle in the housing so as to permit the spindle to shift inward (toward the right) as the conical portion 6 of the spindle, and the surface in which it bears, wear. The spindle 50 may now be rotated at high speed—even up to 20 or 30 thousand revolutions per minute, and no vibration will occur. The bushing 5 is stationary in the housing and the conical portion of the spindle is held 55 closely seated in its conical bearing by the springs 12 which tend to force the sleeve 14 toward the right, Figs. 1 and 2. The sleeve, acting under the pressure of the springs, tends to force the outer ball race 15 axially 60 in the same direction, and this urges the inner set of balls (the ones toward the left, Fig. 1) in the same direction. This set of balls, being seated in an annular groove, urges the ball race 18 in the same direction (axially toward the right) and as the spin-

dle is secured to it, the endwise pressure or thrust holds the conical portion 6 close to its seat. High speed rotation of the spindle causes it to heat appreciably, and this increases its length. Afterward, when the 70 spindle comes to rest, it shrinks to normal length. The resilient take up mechanism in my device compensates for this variation and tends to keep the spindle seated in its conical bearing. Furthermore, the construction not 75 only prevents end play, but permits the grinding wheel to yield (move toward the left) in case its convex surface is pressed too hard or fed too rapidly against the work. Of course the grinding wheel may act on 80 either its convex or concave side, but in the present construction the yielding action occurs when the thrust of the work is toward the left, Fig. 1. The opposite case is illustrated in my aforesaid copending applica- 85

95 It will be noted that the bushing 6 has not only a conical bearing surface, but also a cylindrical bearing surface for the spindle. The advantage of this is, as pointed out in 90 my copending application, that the spindle will still have an acting bearing surface and be prevented from moving crosswise on those occasions when the conical portion of the spindle is not closely seated.

95 It will be noted that the construction is extremely simple, the amount of machine work and threading being reduced to a minimum. The end caps 2, 3 may be pressed in place and the bushing 5 similarly secured. 100 As the disks 12 are all alike, they may be kept in stock and readily replaced if necessary, and the degree of resilience may be varied by either varying the number of disks employed or the thickness of the metal 105 of which they are made.

Having thus described my invention, what I claim as new and desire to secure by Letters Patent is:

1. In a device of the class described, a 110 housing having a conical thrust bearing near one end flaring outward, a spindle having a conical portion adapted to seat in said thrust bearing, non-rotary resilient disks encircling 115 the spindle and adapted to be strained by the housing for yieldingly holding the spindle seated in the thrust bearing, and a ball bearing adapted to coöperate with the thrust bearing to keep the spindle centered in the housing.

120 2. In combination, a spindle having a conical portion, a housing having a conical bearing for the conical portion of the spindle, a ring slidably mounted within the housing and forming a bearing for the spindle, 125 the ring being adapted to exert endwise thrust on the spindle, and a spring encircling the spindle and having a stationary abutment at one end and at the other end exerting pressure axially upon said ring to 130

hold the conical portion of the spindle seated in its conical bearing.

3. In a device of the class described, a housing having a conical thrust bearing near one end flaring outward, and having a supplemental bearing of constant diameter for preventing crosswise movement of the spindle when not seated in the thrust bearing, a second bearing for supporting a distant portion of the spindle, one of the two bearings being fixed in the housing and the other slideable longitudinally therein, and one of said bearings being adapted to exert endwise relative movement between the spindle and the conical thrust bearing, and a spring interposed between two of said bearings for yieldingly holding the spindle seated in the conical thrust bearing.

4. In a device of the class described, a housing having a conical thrust bearing near one end flaring outward, and having a supplemental bearing of constant diameter for preventing crosswise movement of the spindle when not seated in the thrust bearing, a second bearing of constant diameter for supporting a distant portion of the spindle, one of the two bearings being fixed in the housing and the other slideable longitudinally therein, and one of said bearings being adapted to exert endwise relative movement between the spindle and the conical thrust bearing, and a series of resilient concave disks interposed between two of said bearings for yieldingly holding the spindle seated in the conical thrust bearing, said disks being arranged in pairs, concavity to concavity.

5. In a device of the class described, a housing having a conical thrust bearing near one end flaring outward, a spindle having a conical portion adapted to seat in said thrust bearing, resilient disks encircling the spindle and adapted to be strained by the housing, a ball bearing adapted to support one end of the spindle in the housing, said ball bearing being adapted to exert endwise pressure on the spindle, said disks being adapted to act upon said ball bearing for yieldingly urging it in a direction to hold the conical portion of the spindle seated in its bearing.

6. In a device of the class described, a housing having a conical thrust bearing near one end flaring outward, said thrust bearing being fixed against longitudinal movement, the housing having a supplemental bearing of constant diameter for preventing crosswise movement of the spindle when not seated in the thrust bearing, a ball bearing for supporting a distant portion of the spindle, the outer ring of said ball bearing being slideable longitudinally in the housing and the ball bearing being adapted to exert endwise movement on the spindle for holding it seated in the thrust bearing, and a spring interposed between the thrust bearing

and the ball bearing for yieldingly holding the spindle seated in the conical thrust bearing.

7. In a device of the class described, a housing having a conical thrust bearing near one end flaring outward, said thrust bearing being fixed against longitudinal movement, the housing having a supplemental bearing of constant diameter, for preventing crosswise movement of the spindle when not seated in the thrust bearing, a ball bearing for supporting a distant portion of the spindle, the outer ring of said ball bearing being slideable longitudinally in the housing and the ball bearing being adapted to exert endwise movement on the spindle for holding it seated in the thrust bearing, and a series of resilient concave disks interposed between two of said bearings for yieldingly holding the spindle seated in the conical thrust bearing, said disks being arranged in pairs, concavity to concavity.

8. In a device of the class described, a housing provided with a conical thrust bearing, a spindle having a conical portion seating in said bearing, a ball bearing adapted to coöperate with the thrust bearing for supporting the spindle, the ball bearing having two rings with anti-friction balls interposed between them, the inner ring fitting against a shoulder on the spindle and the outer ring being slideable lengthwise in the housing, a spring based at one end upon the housing and at the other end upon one of the rings of the ball bearing, the ball bearing being adapted to transmit thrust endwise to the spindle, a pulley mounted upon the spindle, and a nut screwing on the spindle and adapted to press the pulley against the inner ring of the ball bearing to hold the latter in close engagement with the aforesaid shoulder on the spindle.

9. In a device of the class described, a housing having a conical thrust bearing, a spindle having a conical portion seating in said bearing, a ball bearing having an inner and an outer ring, the inner ring being fast on the spindle and the outer ring being slideable lengthwise on the inner surface of the housing, balls between the two rings, adapted to transmit endwise thrust from one to the other, and a set of non-rotary, resilient, dished disks encircling the spindle between the two bearings and arranged concavity to concavity, said disks having a stationary abutment at one end of the set and at the other end of the set being adapted to exert endwise pressure on the outer slideable ring of the ball bearing to yieldingly hold the conical portion of the spindle seated in its bearing.

In witness whereof I have hereunto subscribed my name.

CARL G. OLSON.
